LAMP AND OPERATING CIRCUIT

Daniel S. Gustin, Bloomfield, N. J., assignor to
 Westinghouse Electric & Manufacturing Company, East Pittsburgh, Pa., a corporation of Pennsylvania

Application November 30, 1938, Serial No. 243,112

16 Claims. (Cl. 176—124)

This invention relates to lamps and operating circuit, and particularly to ultra-violet lamps of the gaseous conduction type, in which the bulb is provided with a window of extremely thin glass for efficiently transmitting the generated light.

One of the principal objects of my invention, generally considered, is the provision of a thin-window, ultra-violet lamp, operating at a lower temperature than those previously on the market without reduction in output, having a longer life and a not much greater wattage, and being capable of manufacture at a smaller material and labor cost, with less shrinkage.

Another object of my invention is the provision of an ultra-violet lamp of the thin window type, having a greater stability and a more uniform output, and capable of being burned in any position and with equal efficiency.

A further object of my invention is the provision of a thin-window, ultra-violet lamp, so constructed that it is less affected by surrounding atmospheric conditions than previous lamps of this type, may be manufactured at smaller cost, and is operable on a double, rather than a single circuit, thereby giving full-wave generation of energy.

A still further object of my invention is the provision of an ultra-violet lamp of the gaseous-conduction type, comprising a pair of cylindrically curved anodes, partially enclosing a heated cathode disposed therebetween, and spaced in a direction transverse to the longitudinal axis of the bulb, a gaseous filling in said bulb admixed with mercury vapour, said bulb having a terminal substantially spherical portion in which is formed a re-entrant bulbous portion, disposed substantially co-axially with the bulb, having its inner part very thin, disposed near to the electrodes, and lying generally parallel to the path of the discharge produced therebetween, for efficiently transmitting the ultra-violet light produced.

Other objects and advantages of the invention, relating to the particular arrangement and construction of the various parts, will become apparent as the description proceeds.

Referring to the drawing:

Figure 1 is a partial elevational and partial vertical sectional view of a lamp embodying my invention, also showing a preferred operating circuit.

Figure 2 is an enlarged horizontal sectional view of the line II—II of Figure 1, in the direction of the arrows.

Referring to the drawing in detail, the lamp

11 of the illustrated embodiment of my invention, comprises a bulb 12, formed of glass pervious to ultra-violet light, provided with a base 13 from which contact prongs 14, 15, 16, and 17 extend. A stem 18, extends from the neck 19 of the bulb and encloses lead-in conductors 21 to 24, inclusive, extending respectively from the contact prongs 14 to 17 inclusive.

Lead-in conductors 21 and 22 connect, respectively, with supports 25 and 26, on which are mounted the electrodes 27 and 28, which function as the anodes of the lamp. These electrodes are desirably formed from rectangular plates of nickel, or other similar material, bent to cylindrical form to partially enclose the space occupied by the electrode 29. The electrode 29 is mounted on supports 31 and 32, respectively extending from lead-in conductors 23 and 24, which serve to transmit heating current to said electrode which functions as the hot cathode of the lamp. It will thus be seen that the members 25, 31, 32 and 26 are alined along the top of the stem 18 or press, and the horizontal plane through the middle of the anodes 27 and 28 includes the axis of the cathode 29.

The electrode 29 is desirably formed of a tungsten wire or filament 33 about which nickel wire 34 is coiled, and the whole again formed into a secondary coil 35, as illustrated most clearly in Figure 2. The nickel wire coating on the coil is, in turn, coated with electron-emission material, such as a mixture of the oxides of barium and strontium, or other alkaline earth oxides, as will be understood.

35 In order to efficiently transmit the ultra-violet light generated when a discharge is produced from the cathode 29 to the anodes 27 and 28, the bulb 12 is formed with a reentrant bulbous portion 36, preferably substantially spherical and lying on the longitudinal axis of the bulb 12, that is substantially coaxial with said bulb with its inner portion very thin, lying close to the electrodes, and extending approximately parallel, or uniformly spaced with respect to the line of discharge therebetween.

40 In manufacturing lamps such as described, the bulb is first thoroughly cleaned and the spherical end portion heated and drawn inward, being evenly shaped into as nearly spherical form as possible, and preferably of a relative size as illustrated in Figure 1. The thickness of the window 36 adjacent the electrodes, is desirably maintained between .002" and .003", tapering from the periphery where it joins the main spherical end portion of the bulb 12.

After assembling the bulb with the electrodes, exhausting and filling it with an inert gas, such as about 5 mm. of pure argon, and a drop (about 200 mg.) of mercury, the lamp may be operated in a circuit such as is diagrammatically illustrated in Figure 1. The reference character 31 represents a transformer, the primary winding 38 of which, is connected across the line, and the terminals of the secondary 39 of which are respectively connected to the anodes 27 and 28. The cathode 29 is heated by having its contact posts 16 and 17 connected to the terminals of a supplemental secondary winding 41 through conductors 42 and 43. The cathode should not be connected in the circuit with the anodes 27 and 28 until after it has been heated to operating temperature. For this reason, the circuit through the line 44 to the center tap of the secondary winding 39, is not completed by closing the switch or time-delay relay 45, until after the connection with the line has been made for a sufficient length of time to heat the cathode 29 to operating temperature.

In other words, the procedure of putting the lamp into service is to first close the line switch until the cathode reaches operating temperature, and then close the switch or relay 45. If a time-delay relay is employed, it, of course, may be formed as a part of the line switch (not shown) so that the circuit through 44 is not completed until the cathode 29 has been heated to the desired temperature.

From the foregoing disclosure it will be seen that I have provided a better thin-window mercury vapour lamp than previous constructions, said lamp consisting of two anodes and a cathode, the cathode being desirably nickel wire wound over tungsten and coated with a mixture of oxides of barium and strontium. The cathode, in a preferred embodiment, is desirably operated by a current of about eight amperes having a potential of about two volts. The open circuit potential across the anodes, in such an embodiment of the invention, may be forty-four volts; with the lamp, when operating, drawing about one ampere from the center tap through the conductor 44 and the voltage across the anodes dropping to about fourteen.

Tests on lamps such as disclosed, have shown that after 200 hours burning a relatively small drop in initial output occurs, while previous constructions have shown a much greater loss in efficiency.

Although a preferred embodiment of my invention has been disclosed, it will be understood that modifications may be made within the spirit and scope of the appended claims.

I claim:

1. An ultra-violet lamp of the gaseous-conduction type comprising an enclosing bulb, a pair of arcuate anodes concave toward one another, a cathode disposed therebetween, means for heating said cathode, a gaseous filling in said bulb admixed with mercury vapor, and a re-entrant bulbous portion extending from an end of said bulb toward said electrodes, the inner part of the said re-entrant portion being very thin, lying close to the electrodes and extending approximately parallel to the line of discharge therebetween, for efficiently transmitting ultra-violet light produced.

2. An ultra-violet lamp of the gaseous-conduction type comprising a bulb, a pair of anodes disposed therein and curved concavely toward one another, a cathode positioned therebetween,

means for heating said cathode, and a gaseous filling in said bulb admixed with mercury vapor, said bulb having a thin window portion disposed close to said electrodes and lying in a plane disposed approximately parallel to the line of discharge in said bulb.

3. An ultra-violet lamp of the gaseous-conduction type comprising an enclosing bulb, a pair of anodes spaced in a direction transverse to the longitudinal axis of said bulb and presenting concave surfaces to one another, a cathode disposed therebetween, means for heating said cathode, a gaseous filling in said bulb admixed with mercury vapor, and a re-entrant bulbous portion, substantially coaxial with said bulb, extending from an end of said bulb toward said electrodes, the inner part of said re-entrant portion being very thin for efficiently transmitting ultra-violet light.

4. An ultra-violet lamp of the gaseous-conduction type comprising an enclosing envelope, a pair of anodes, a cathode disposed therebetween, said anodes being curved to partially enclose said cathode, means for heating said cathode, a gaseous filling in said envelope admixed with mercury vapor, said envelope having a base and a terminal substantially spherical portion, and a re-entrant bulbous part extending from said spherical portion toward said electrodes, coaxially with said envelope, the inner portion of said re-entrant part being very thin for transmitting ultra-violet light.

5. An ultra-violet lamp of the gaseous-conduction type comprising an enclosing envelope, a pair of electrodes adapted to function as anodes, an intermediate electrode disposed therebetween, said anodes consisting of plates bent to partially enclose said cathode, means for heating said intermediate electrode to cause it to function as a cathode, a gaseous filling in said envelope admixed with mercury vapor, and a re-entrant bulbous portion extending from an end of said envelope toward said electrodes and disposed substantially co-axially with said envelope, the inner part of said re-entrant portion being thin enough to efficiently transmit ultra-violet light.

6. An ultra-violet lamp of the gaseous-conduction type comprising an enclosing envelope, a pair of anodes concave towards each other, a cathode disposed therebetween, means for heating said cathode, a gaseous filling in said envelope admixed with mercury vapor, and a re-entrant bulbous portion extending from an end of said envelope toward said electrodes, the inner part of said re-entrant portion being very thin and disposed close to said electrodes for efficiently transmitting ultra-violet light produced thereby.

7. An ultra-violet lamp of the gaseous-conduction type comprising an enclosing envelope, a pair of curved electrodes concave toward each other and adapted to function as anodes, an intermediate electrode disposed therebetween and partly enclosed thereby, means for heating said intermediate electrode to cause it to emit electrons, a gaseous filling in said envelope admixed with mercury vapor, and a re-entrant bulbous portion extending from an end of said envelope towards said electrodes, the inner part of said re-entrant portion being very thin, lying generally parallel to the path of discharge producible between said electrodes, and efficiently transmitting ultra-violet light which is generated by such a discharge.

8. An ultra-violet lamp of the gaseous-conduction type comprising an enclosing bulb, a pair of anodes concave toward one another, a cathode disposed therebetween, means for heating said cathode to cause it to emit electrons, argon in said bulb admixed with mercury vapor, and a re-entrant portion extending from an end of said bulb toward said electrodes, the inner part of said re-entrant portion being sufficiently thin to efficiently transmit ultra-violet light generated by a discharge between said electrodes.

9. An ultra-violet lamp of the gaseous-conduction type comprising an enclosing bulb, a pair of anodes spaced in a direction transverse to the longitudinal axis of said bulb, a cathode disposed therebetween, said anodes being bent to more completely surround said cathode, means for heating said cathode, a gaseous filling in said bulb admixed with mercury vapor, said bulb having a base and a terminal substantially spherical portion, a re-entrant bulbous part extending from said spherical portion towards said electrodes and disposed substantially co-axially with said bulb, the inner portion of said re-entrant part being very thin, disposed near to said electrodes and lying generally parallel to the path of discharge produced therebetween, for efficiently transmitting the ultra-violet light produced.

10. An ultra-violet lamp of the gaseous-conduction type comprising an enclosing envelope, a pair of electrodes spaced in a direction transverse to the longitudinal axis of said envelope and designed to act as anodes, an intermediate electrode disposed therebetween, said anodes being curved so as to more completely surround said cathode, means for heating said intermediate electrode to cause it to emit electrons and act as a cathode, a filling of argon at a pressure of about 5 mm. and admixed with mercury vapor, said envelope having a base at one end and a substantially spherical portion at the other end, said spherical portion being formed with a re-entrant part extending toward the electrodes and disposed substantially co-axially with said envelope, the inner portion of said re-entrant part being very thin, disposed near to said electrodes, and lying generally parallel to the path of discharge which may be produced therebetween, for efficiently transmitting ultra-violet light.

11. An ultra-violet lamp of the gaseous-conduction type comprising an enclosing bulb, a pair of anodes formed concave toward one another, a cathode disposed therebetween, a gaseous filling in said bulb admixed with mercury vapor, and a re-entrant bulbous portion extending from an end of said bulb toward said electrodes, the inner part of said re-entrant portion being very thin to provide for the transmission of ultra-violet light.

12. An ultra-violet lamp of the gaseous-conduction type comprising an enclosing bulb, a pair of anodes, each consisting of a plate bent to more completely enclose the space therebetween, a cathode disposed therebetween, said cathode comprising a tungsten wire in helical form over which is wound a nickel wire coated with electron-emitting oxides, means for introducing current to said tungsten wire for heating the cathode to electron-emitting temperature, a gaseous filling in said bulb admixed with mercury vapor and a re-entrant portion extending from an end of said bulb toward said electrodes, the inner part of said re-entrant portion being very thin and efficiently transmitting ultra-violet light.

13. An ultra-violet lamp of the gaseous-con-

duction type comprising an enclosing envelope formed of glass pervious to ultra-violet light, a pair of anodes concavely curved toward one another, a cathode disposed therebetween, means for heating said cathode, a gaseous filling in said bulb admixed with mercury vapor, and a re-entrant portion extending toward said electrodes and formed very thin for efficiently transmitting ultra-violet light.

14. In combination with a lamp of the gaseous-conduction type comprising an enclosing envelope, a pair of electrodes adapted to function as anodes, an intermediate electrode disposed therebetween, said anodes being concave toward each other to more completely enclose said intermediate electrode, and means for operating said lamp comprising a transformer, a supplemental winding on said transformer, electrical connections only between the main secondary winding terminals of said transformer and said first mentioned electrodes, and between said supplemental winding and the terminals of said intermediate electrode to heat it to electron-emitting temperature, and means for connecting said supplemental secondary winding to the mid-point of the main secondary winding when the intermediate electrode has reached operating temperature, in order to then cause it to function as a cathode with the associated electrodes as anodes, independent of any temporary starting means.

15. An ultra-violet lamp of the gaseous-conduction type comprising an enclosing bulb, a pair of anodes formed concave toward one another, a cathode disposed therebetween, a gaseous filling in said bulb admixed with mercury vapor, a re-entrant bulbous portion extending from an end of said bulb toward said electrodes, the inner part of said re-entrant portion being very thin to provide for the transmission of ultra-violet light, and means for operating said lamp, comprising a transformer having a supplemental winding, electrical connections only between the main secondary winding terminals of said transformer and said anodes, and between said supplemental winding and the terminals of said intermediate electrode to heat it to electron-emitting temperature, and means which connect said supplemental secondary winding to the mid-point of the main secondary winding when the intermediate electrode has reached operating temperature, in order to then cause it to function as a cathode with the associated electrodes as anodes, independent of any temporary starting means.

16. In combination, a lamp of the gaseous conduction type comprising an enclosing envelope, an electrode adapted to function as an anode, an electrode comprising a filament, and means for operating said lamp comprising a transformer, a supplemental winding on said transformer, an electrical connection between a main secondary winding terminal of said transformer and said first-mentioned electrode, electrical connections between the terminals of said supplemental winding and said filamentary electrode to heat it to electron-emitting temperature, and normally open switch means for connecting said supplemental secondary winding to the main winding when the filamentary electrode has reached operating temperature, in order to only then cause it to function as a cathode with the first-mentioned electrode as an anode, independent of any temporary starting means.
